Des. 216,334
Patented Dec. 16, 1969

216,334

STRINGED MUSICAL INSTRUMENT

Walter J. Pelensky, 19C Manheim Gardens,
Philadelphia, Pa. 19144

Filed Mar. 28, 1968, Ser. No. 11,182

Term of patent 14 years

Int. Cl. D17—03

U.S. Cl. D56—1

Fig. 2

Fig. 1.

Fig. 4

Fig. 3

Fig. 5

FIG. 1 is a perspective view of a stringed musical instrument, specifically, a Ukrainian Kobza, showing my new design;

FIG. 2 is a fragmentary perspective view, showing the peghead from a different angle;

FIG. 3 is a face view;

FIG. 4 is a left side elevation;

FIG. 5 is a right side elevation.

Portions of the drawings are shaded to indicate contrast.

I claim:

The ornamental design for a stringed musical instrument, as shown and described.
